UNITED STATES PATENT OFFICE.

CYRUS H. LATHAM, OF LOWELL, MASSACHUSETTS, ASSIGNOR TO HIMSELF, EDWARD P. WOODS, AND DANIEL SHERWOOD, OF SAME PLACE.

DESIGN FOR MATCH-STAND, &c.

Specification forming part of Design No. 6,144, dated September 17, 1872.

To all whom it may concern:

Be it known that I, CYRUS H. LATHAM, of Lowell, in the county of Middlesex and State of Massachusetts, have invented a Design for a Stand for Holding Matches, Tooth-Picks, &c., of which the following is a specification:

The nature of my design is fully represented in the accompanying drawing, to which reference is made.

In the drawing, A represents the base of the stand, which may be made of wood or cast in metal, as desired. It is provided with a cavity, B, which is sanded or roughened in any way to make a frictional surface upon which to ignite a match. To this base is secured a holder, C, made up of twisted wire, in the manner described in the reissued Letters Patent No. 4,209, granted to me December 20,

1870. The ends of these wires are inserted in the base by casting to the metal or being forced into holes in the wood.

The upper part of the base may be ornamented with a metal ring cast thereto, and in which is inserted the wires C. A glass, porcelain, or other cup is inserted within the wire cup to hold the articles.

Claim.

The design for a stand for matches, tooth-picks, &c., substantially as shown in the accompanying drawing.

CYRUS H. LATHAM.
